UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

APPARATUS FOR AIMING GUNS.

1,310,139.

Specification of Letters Patent. Patented July 15, 1919.

Application filed July 30, 1917. Serial No. 183,596.

To all whom it may concern:

Be it known that I, EUGÈNE SCHNEIDER, a citizen of the French Republic, resident of Le Creuzot, France, have invented a new and useful Improvement in Apparatus for Aiming Guns, which is fully set forth in the following specification.

This invention has for its object to provide an improved apparatus for aiming guns. Forms of apparatus for aiming guns consisting of a combination of elevating mechanism and sighting mechanism are already known wherein the sighting mechanism connected to one of the trunnions of the gun barrel or of the gun cradle, is movable in rigid connection with a graduated drum bearing on its cylindrical surface indexes of elevations (angles of elevation of the gun barrel) and also if desired, bearing on its base indexes of ranges corresponding to said elevations, each index of ranges corresponding to one and the same type of propelling charge for the same projectile or for different projectiles.

When, with this known apparatus, it is desired to determine for any one of the types of projectiles which it is desired to use, the corresponding propelling charge and the elevation for a given range, the gunner has to consult printed firing tables.

The improved apparatus forming the subject matter of the present invention is designed to do away with all necessity for using firing tables for the purpose of ascertaining the propelling charge to be used and the elevation to be given, for firing any given projectile with any given range.

This improved apparatus consists in principle in supplementing the usual drum bearing the indexes of elevations, with an indicating plate which is independent of the said drum and is mounted so as to be capable of movement about the axis of the said drum. This plate is provided with a continuous scale of ranges. Said plate bears also concentrically to this scale and for each of the types of projectiles which the gun may be called upon to fire, two scales divided into as many sectors as there are propelling charges that may have to be used, and consequently as many initial velocities that may be required to be given to these projectiles. In each sector the propelling charge is indicated on one of the divisions, and on the other division there is indicated the eleva-

tion which is to be employed in order to produce the range which is read off from the common central scale division.

This plate is a simple indicating disk to be used instead of the firing table. When the gun layer has read off this plate not only the elevation but the kind of propelling charge corresponding to said elevation for a given range, and for the selected type of projectile, he then makes use of the usual drum for elevations for elevating the gun barrel in the ordinary way by means of the sighting apparatus and the spirit level.

One embodiment of this invention is illustrated by way of example in the accompanying drawings in which:

Figure 1 is a front elevation of the general arrangement of elevating apparatus and sighting apparatus in combination with the improved indicating apparatus forming the subject matter of the present invention.

Fig. 2 is a side elevation partly in cross section along the axis of the trunnions of the gun cradle.

Fig. 3 is a view partly in elevation and partly in section on the line III—III of Fig. 2, the divisions of the plate being visible through a window in a casing that is fixed to a support pivoted to one of the trunnions of the gun cradle.

Fig. 4 is a corresponding view showing the opening in the indicating plate in coincidence with the window in the casing, and the plate fixed in this position.

The gunner is then able to read through the window the scale divisions of ranges corresponding to the different types of projectiles, that are marked on the base of the usual elevation drum.

Fig. 5 is an elevation of the indicating plate showing through the opening in the said plate and after part has been broken away, the scale divisions of the ranges of the elevation drum in rigid connection with the sighting apparatus; the plate being assumed to be fixed in the position shown in Fig. 4.

In these figures, A indicates the general arrangement of the sighting apparatus of any known type and comprising a spirit level B. This general arrangement is mounted in a known manner so as to be capable of being displaced angularly about an axis X—X parallel to the axis Y—Y of the trunnions of the gun barrel or gun cradle. This

displacement may be given to the apparatus by an actuating mechanism such as a worm screw D whose spindle d is journaled in a support formed in a casing E fixed to the 5 bracket F around which the apparatus can rotate. In rigid connection with the sighting apparatus, the screw D actuates by means of a separate screw-thread with a suitable reduction of speed, a drum of elevations C. The said drum bears on its cylindrical surface the usual scale divisions (in twentieths of a degree for instance) visible through a window e in the casing E. (See Fig. 2.) A register mark E¹ provided 10 in the metal of the casing, projects over the window e.

On the outer surface of its base the drum C is provided with two scales of ranges C¹ and C² (divided for instance into hundreds 20 of meters). These divisions represent the ranges corresponding to the elevations located opposite them on the cylindrical surface of the drum when the gun is fired with a single given propelling charge; the scale 25 C¹ being used for firing one type of projectile (for instance a steel shell), while the other scale C² represents the ranges for firing with the same reduced charge another type of projectile (for instance a shell of 30 steeled cast iron or a shrapnel shell).

For the sake of clearness of the drawings and of the description, it is assumed that the apparatus is designed solely for two types of projectiles; it is however to be understood 35 that the drum may be provided with scales of ranges C¹, C², etc., corresponding in number with the number of types of projectiles which the gun may be called upon to fire.

40 In the outer base of the casing E there is provided a window E² in which there is formed a radial register mark G.

In a bearing E³ formed in the end of the casing E along the axis X—X, there is pivoted 45 on a journal h the indicating plate H which can be turned by hand by means of a knurled knob I.

This plate H is formed with an opening H¹ which can be brought opposite the window E² of the casing when it is desired to read through the said window the scale of 50 ranges C¹, C², etc., engraved on the drum of elevations C. This is the position shown in Fig. 4. The plate may however be fixed in this position on the casing E, for instance by 55 means of the simple device shown. A spiral spring J is engaged with one end j in the bearing E³, while its other end j¹ which is bent outward, bears against the inner surface 60 of the knurled knob I. (See Fig. 3.) When the said knob has been operated so as to bring the plate H into the position shown in Fig. 4, the end j¹ of the spring will engage in a notch i formed in the inner surface of 65 the knob I.

On its outer face the plate H bears, starting from one edge of the opening H¹, a continuous divided scale K of ranges (Fig. 5) common to all the types of projectiles.

For each of the types of projectiles that 70 are employed, the circumference of the plate H is divided into a series of consecutive sectors L, L¹, L², L³, L⁴, etc.; each of these sectors corresponds to the use of one kind of propelling charge for the ranges comprised 75 between its ends on the divided scale K. For instance the outer sector L corresponds to the use of the propelling charge 00, for ranges varying between 10500 and 12000 meters with a projectile of steeled cast iron. 80 The inner sector L corresponds to the use of the charge 00, for ranges varying between 8400 and 10200 meters with a steel projectile.

In each of the sectors there are inscribed 85 opposite the ranges the elevations for each of the types of projectiles. Thus for instance for a range of 11500 meters, with a propelling charge 00 and a shell of steeled cast iron, the gun barrel should receive the 90 elevation 730 (i. e., 730 twentieths of a degree).

Similarly, for a range of 10000 meters, with the propelling charge 00 and a steel shell, the gun barrel should receive the elevation 95 773 twentieths of a degree.

It will be perceived that by simply reading off the indicating plate H, the gunner will be able to ascertain at once the kind of propelling charge which he must use, as well 100 as the corresponding elevation to be given to the gun barrel for any given range and any one of the types of projectiles that is to be used.

When once these indications have been 105 ascertained, the elevation of the gun barrel is effected in the usual manner. If the elevation to be given to the gun barrel is for instance 773 twentieths of a degree, the division 773 on drum C must be brought opposite 110 the register mark E¹, and this operation, assuming the axis of the gun barrel to be horizontal, will have the result of inclining the sighting apparatus through an angle of 773 twentieths of a degree. 115

Then by operating the elevating mechanism of the gun in such a manner as to bring back the sighting apparatus into its vertical position, which is indicated by the return of the bubble of the spirit level B between its 120 register marks, the axis of the gun barrel will receive the desired inclination.

As hereinbefore stated, when it is desired to fire different types of projectiles, while using always the same reduced charge, the 125 elevation of the gun may be effected by simply moving the scale of ranges C¹, C², etc., corresponding to the desired type of projectile, into the requisite position by actuating the screw D; said scale being placed in 130

61.5

3

such a manner that the selected range shall be situated opposite the register mark G of the casing. First, however, the opening H¹ of the disk H will have been brought into coincidence with the window of the casing (Fig. 4).

What I claim is:—

1. For use with combined apparatus for sighting and elevating guns, the combination with the usual drum bearing a scale of elevations, of a disk mounted so as to be freely movable around the axis of said drum, bearing a continuous scale of ranges and also provided, opposite to said scale of ranges, with a series of consecutive sectors corresponding each to one kind of propelling charge, each of said series bearing a scale of elevations corresponding to each type of the various projectiles which are to be fired from the gun, whereby the gun-layer, without consulting firing tables, can, from a direct reading of the disk, ascertain the propelling charge and the gun elevation required to project to any desired range any desired one of the various types of projectiles for which the said disk is divided.
2. For use with combined apparatus for sighting and elevating guns, the combination with the usual drum bearing a scale of elevations, of a disk mounted so as to be freely

movable around the axis of said drum, bearing a continuous scale of ranges and also provided, opposite to said scale of ranges, with a series of consecutive sectors corresponding each to one kind of propelling charge, each of said series bearing a scale of elevations corresponding to each type of the various projectiles which are to be fired from the gun, and a casing having a window, inclosing said disk and said elevation drum, 35 said disk having an aperture from one edge of which the scales on said disk start, said aperture having the same dimensions as those of said window in said casing, whereby when said aperture has been brought and locked into a position of coincidence with said window, the gun-layer will be able to read through said window the numbers denoting the propelling charge and gun elevation that are required to be employed with 40 any desired type of projectile and any desired range.

In testimony whereof I have signed this specification in the presence of two subscribing witnesses.

EUGÈNE SCHNEIDER.
